PUFFING GUN

Henry S. Crosby, Long Lake, Minn., and Thomas P. Ring, Buffalo, N. Y., assignors to General Mills, Inc., a corporation of Delaware

Application October 31, 1940, Serial No. 363,686

8 Claims. (Cl. 99—238)

This invention relates to puffing guns and to mechanism of this type for puffing cereals or alimentary pellets made from cereals and more particularly to means for heating the barrels of such guns with gas.

An object therefore of this invention is to provide an efficient means for heating such a gun barrel with gas.

This and other objects as will hereinafter appear are accomplished by this invention which is fully described in the following specification and shown in the accompanying drawings in which

Figure 1 is a perspective view of the puffing gun showing parts of the carriage and jacket for the barrel cut away to show the burners;

Fig. 2 is an enlarged partial longitudinal section through the puffing gun barrel showing particularly the gas burners and the ignition device;

Fig. 3 is a diagram of connections for the ignition apparatus;

Fig. 4 is a partial perspective view of the open end of the puffing gun barrel;

Fig. 5 is a section on the line 5—5 of Fig. 2;

Figs. 6 and 7 are partial enlarged sections on the lines 6 and 7, respectively, of Fig. 2;

Fig. 8 is a partial enlarged perspective view of the burners; and

Fig. 9 is a cross section showing an alternative form of burner.

This invention relates primarily to a new and efficient means for heating a puffing gun, many of the other details of the gun barrel and its mounting being old and forming the subject of separate patent applications. The gun barrel shown generally by the numeral 15 is rotatably mounted as will presently be described for rotation about its longitudinal axis in an oscillatable carriage having side channel members 16, 17, the latter being broken away, as shown in Fig. 1, in order the better to show the gun barrel. These channels are connected by end members 18, 19 and 20 and the carriage as a whole being mounted to oscillate about an axis at right angles to the longitudinal axis of the gun barrel and mounted in suitable bearings, not shown, in a main frame 21.

Referring to Fig. 2, a gun barrel proper 30 is closed at one end by means of a gas-tight head 31 while the open end is closed by a lid 32 which is hingedly mounted on arms 33 which in turn are pivotally mounted on a pin 34, as described in detail in the patent to Thomas R. James for Puffing gun lid release mechanism, No. 2,210,294, granted August 6, 1940. The head 31 has ax-

ially extending therefrom a shaft 35 mounted in a suitable bearing 36 which is carried by the carriage member 18.

For mounting the opposite end of the gun barrel, we have provided a ring 37 which is concentric with the gun barrel and which is secured thereto at intervals by means of a series of posts 38 which are electrically welded to the gun barrel and to the ring thereby leaving openings therebeneath for the passage of gas as will presently be seen. This ring rolls on rollers 39 journaled on pins 40 on the end member 20. When the gun is inverted this ring rests on the end member 19 but does not rotate in this position.

15 The gun barrel is provided with a series of outwardly projecting lugs 45 and on each longitudinal roll of these we mount a gas burner 46 by means of laterally extending ears 47 and cap screws 48. These cap screws also pass through an insulating jacket which is preferably made up of three sections 49, 50, 51, as shown in Fig. 5, with cover plates 52 covering the joints where these sections meet.

25 It will be observed that the jacket 49 is spaced from the gun barrel so as to provide an annular space 53 in which the burners are located and which serves as a combustion space for the burning gas which heats the gun barrel.

Each of these burners is provided with a series 30 of slits 60 which face in the one direction as shown in Figs. 6 and 8 and a series of slits 61 which face substantially at 90° therefrom. These burners are closed at both ends and these slits are preferably made with thin rotary cutters 35 so as not to permit a flame to flash back through them, the gas issuing therefrom, as will presently be seen, being a combustible mixture.

Each of the burners is provided at its rear end with a flanged plate by means of which it is bolted 40 to a baffle ring 62 and to a pipe 65, these pipes extending radially from an annular flange 66 on the end 31 of the gun barrel, this flange providing a gas space 67. The flange 66 is ground at its end to form a gas-tight bearing with a 45 stationary gas ring 68 which is pressed by a bearing plate 69 and a spring 70 which takes the bearing on a retaining ring 71 which surrounds and bears against a split ring 72 which is made up of two half circular pieces which fit into a 50 depression 73 in the shaft 35 so that when assembled the retaining ring holds the split ring 72 assembled on the shaft. The combustion space 53 is closed at the forward end by the baffle ring 63 and is partially closed at the rear 55 end by an apron 73 but communicates with the

atmosphere through openings 74 and an annular space 75.

A combustible mixture of gas and air is fed to the gas ring 68 through a pipe 88 which connects, as shown in Fig. 1, with an elbow 81, a rubber hose 82, and a pipe 83 with a connection 84 which is in axial alignment with the trunnions (not shown) of the carriage and is rotatably mounted in a stationary member 85. The latter connects through a rubber hose 86 with a gas and air mixer 87 which receives air under regulated pressure through a pipe 87^a and gas through a pipe 88 and a valve 89 having a lever 90 within easy reach of an operator for cutting off heat to the puffing gun while rotation of the barrel is stopped for discharging and recharging. The air continues to flow. The valve lever 90 also carries a pin 91 which moves a lever 92 about a fulcrum 93 to open an electric switch 94 in the circuit 94^a when the valve is closed, thereby stopping a motor for driving the barrel as will later be described.

For igniting the combustible mixture we have provided a spark plug 95 which is screwed into a threaded opening 96 (Fig. 8) in one of the ears 47 so that it lies adjacent one of the burners. This spark plug has an outer metal cap 97 which makes contact on each revolution of the gun barrel with a stationary brush 98 which is yieldingly mounted by means of springs 99 on a metal post 100, the latter being mounted on an ignition block 101 on the member 28 from which it is insulated by the block 101. The post 100, however, is electrically connected to a lead 102 which connects through a secondary S of an ignition coil 103 (Fig. 3), the other side of this coil being grounded. The primary coil P of this ignition coil connects through a suitable source of alternating current 104. Thus upon contact being made between the cap 97 and the stationary brush 98, a high tension current sufficient to produce a spark across the points of the spark plug will be impressed upon the latter, once for each half cycle of applied alternating current so long as the cap 97 remains in contact with the brush 98. This insures the combustible mixture with the annular combustion space 53 being ignited on each revolution of the gun barrel.

The rotation of the gun barrel is accomplished by means of a motor 110 (Fig. 1) which drives through a belt 111 a suitable reduction gearing (not shown) to a worm wheel 112 on the shaft 35. The operation of this motor is controlled by the switch 94.

The lid 32 is opened by means of a trip lever 120 which moves down beneath a trip finger 121 when the gun barrel is tilted forward, this trip finger yielding to permit the trip lever to pass due to the action of a spring 122.

An alternative form of burner shown in Fig. 9 has been found to be particularly useful with gases of different heating qualities. This consists of a rectangular tube 120 having a longitudinal slot 121 cut therein.

Across this slot is placed a longitudinally rolled or folded sheet of wire gauze 122 of about thirty-eight mesh to the inch which is held in place by a long metal strap 123 secured thereto by welding 124 at intervals on one or both sides of the strap while the latter is held firmly pressed against the rolled gauze sheet. Thus the gas and air mixture burns along both edges of the strap 123.

The other details of the puffing gun, and particularly the method of loading, closing and fir-

ing the gun, are not shown in detail since they show no part of the present invention.

While we have shown but a single embodiment of our invention, it is to be understood that it is capable of many modifications. Changes, therefore, in the construction and arrangement may be made which do not depart from the spirit and scope of the invention as disclosed in the appended claims.

We claim as our invention:

1. In a puffing gun, a barrel rotatable about its longitudinal axis and closed at one end, a lid hinged to the barrel for closing the other end, a heat-insulating jacket secured to and about the gun barrel and spaced therefrom so as to provide an annular space, a plurality of spaced burners extending into this space, means for supplying a combustible mixture to said burners while the barrel is rotated, and means for igniting said mixture at the burners.
2. In a puffing gun, a barrel rotatable about its longitudinal axis and closed at one end, a lid hinged to the barrel for closing the other end, a jacket secured about the gun barrel and spaced therefrom so as to provide an annular space, a plurality of spaced burners extending into this space, said burners being secured to the gun barrel and extending substantially the length of the gun barrel and having burner openings throughout substantially the length of the burners, means for supplying a combustible mixture to said burners, and means for igniting said mixture at the burners while the barrel is rotating.
3. In a puffing gun, a barrel rotatable about its longitudinal axis and closed at one end, a lid hinged to the barrel for closing the other end, a jacket secured to the gun barrel and spaced therefrom so as to provide an annular space, a plurality of spaced burners extending into this space, the space being closed at the closed end of the barrel and open at the opposite end so that the exhaust gases pass out at the end of the barrel having the lid, means for supplying a combustible mixture to said burners, and means for igniting said mixture at the burners.
4. In a puffing gun, a barrel rotatable about its longitudinal axis and closed at one end, a lid hinged to the barrel for closing the other end, a jacket secured to the gun barrel and spaced therefrom so as to provide an annular space, a plurality of spaced burners extending into this space, means for supplying a combustible mixture to said burners, and means carried by the barrel for igniting the combustible mixture.
5. In a puffing gun, a barrel rotatable about its longitudinal axis and closed at one end, a lid hinged to the barrel for closing the other end, a jacket secured to the gun barrel and spaced therefrom so as to provide an annular space, a plurality of spaced burners extending into this space, means for supplying a combustible mixture to said burners, and high tension electric means carried by the barrel for igniting the combustible mixture.
6. In a puffing gun, a barrel rotatable about its longitudinal axis and closed at one end, a lid hinged to the barrel for closing the other end, a jacket secured to the gun barrel and spaced therefrom so as to provide an annular space, a plurality of spaced burners extending into this space, means for supplying a combustible mixture to said burners, and high tension electric means carried by the barrel for igniting the combustible mixture on each revolution of the barrel,

said means including a stationary insulated brush, and a spark plug having spaced electrodes extending into said space and a metal cap adapted to engage the brush on each revolution of the barrel.

7. In a puffing gun, a barrel rotatable about its longitudinal axis and closed at one end, a lid hinged to the barrel for closing the other end, a jacket secured to the gun barrel and spaced therefrom so as to provide an annular space, a plurality of spaced burners extending into this space, means including parts located about the axis of the barrel for supplying a combustible

mixture to said burners, and means for igniting said mixture.

8. In a puffing gun, a barrel rotatable about its longitudinal axis and closed at one end, a lid hinged to the barrel for closing the other end, a jacket secured to the gun barrel and spaced therefrom by means of bosses integral with the barrel so as to provide an annular space, a plurality of spaced burners extending into this space, and means for supplying a combustible mixture to said burners.
